UNITED STATES PATENT OFFICE

154,772

DESIGN FOR A FIRE EXTINGUISHER

David F. Hack, Danbury, Conn., assignor to D. F. Hack, Inc., Danbury, Conn., a corporation of Connecticut

Application October 1, 1947, Serial No. 141,703

Term of patent 3½ years

(Cl. D16—2)

To all whom it may concern:

Be it known that I, David F. Hack, a citizen of the United States, residing at Danbury, in the county of Fairfield and State of Connecticut, have invented a new, original, and ornamental Design for a Fire Extinguisher, of which the following is a specification, reference being had to the accompanying drawing, forming part thereof.

Fig. 1 is a perspective view of a fire extinguisher, showing my new design; and

Fig. 2 is a top plan view thereof.

I claim:
The ornamental design for a fire extinguisher, as shown.

DAVID F. HACK.
